(57) **CLAIM**

The ornamental design for a display screen, or portion thereof, having a graphical user interface, as shown and described.

DESCRIPTION

FIG. 1 is a front view of a display screen, or portion thereof, having a graphical user interface showing a first embodiment of the new design; and,

FIG. 2 is an enlarged view of the callout region 2 of FIG. 1. The broken lines of even length showing the remainder of the display screen, or portion thereof, having a graphical user interface is for environmental purposes only and forms no part of the claimed design. The broken lines of uneven length labeled FIG. 2 in FIG. 1 indicate portions of the graphical user interface that are enlarged for magnification purposes in FIG. 2 and form no part of the claimed design.
